MANIFOLDING ATTACHMENT FOR
TYPEWRITERSAllen B. Cooke, Chicago, Ill., assignor to United
Autographic Register Co., a corporation of Illinois

Application April 3, 1939, Serial No. 265,854

5 Claims. (Cl. 197—126)

This invention relates to adapters for typewriters having an upwardly movable platen, to facilitate the handling of carbon slips in connection with continuous-form stationery, and more particularly to an improved typewriter attachment having an extensible frame supported on a rail provided in the rear of the typewriter so that the attachment will travel laterally with the platen carriage and will be rocked by the platen about said track as a fulcrum.

The primary object of the invention is to provide an inexpensive, light attachment which may be readily attached to the platen carriage of a typewriter and has a latch which is thrown to operative or inoperative position with the upward movement of the platen.

A further object of the invention is to provide a tiltable typewriter attachment which is fulcrumed about a point in rear of the typewriter, so that when the platen is down in its normal writing position, the extensible frame will tend to move forwardly with the stationery under the influence of gravity, and when the platen is raised to strip the carbon into the next succeeding set of forms, the frame will be tilted backwardly so that the carbon holder will tend to travel rearwardly under the influence of gravity to a locked position.

The present invention is an improvement over the device shown in Jensen Patent No. 2,109,293, issued February 22, 1938.

The invention is illustrated in a preferred embodiment in the accompanying drawings, in which—

Figure 1 is a side elevational view of the attachment mounted on a typewriting machine which is shown brokenly, the dotted lines indicating the elevated position of the device when the platen is raised; Figure 2 is a broken plan view of the device and supporting track with the stationery and carbon removed; and Figure 3 is a fragmentary longitudinal sectional view, taken as indicated at line 3 of Figure 2.

In the embodiment illustrated, A designates a supporting frame; B, an extension frame slidably mounted for forward and rearward movement on the frame A; C, a carbon holder adjustably mounted on the frame B; and D, a latching device for the frame B.

The device may be adapted for use on any typewriting machine 4 having a transversely shiftable carriage 5 with an upwardly-movable platen. The typewriter carriage is shown with a fixed cross-bar 6 on which the front end of the attachment is saddled, and the carriage has a

cross-bar 7 which moves upwardly with the platen. A track 8 in the form of a channel member is supported by the main frame of the machine on rearwardly extending arms 9 which are braced by legs 10.

The supporting frame A is shown with a longitudinally extending plate 11 provided with a slot 12. A pair of curved slotted saddle members 13 is secured to the front end of the plate 11, and a forwardly extending pair of yoke members 10; 14 is also secured to the plate 11, so that to attach the device it is merely necessary to slip the yoke members over the bar 7 and slip the saddle members over the bar 6. A downwardly extending bracket 15 is provided with a roller 16 which 16 travels on the track 8 and supports the attachment. The bifurcated members 14 serve also as lateral guides for stationery passing over the attachment to the platen.

A pair of longitudinally extending angle bars 17 20 is spot welded to the lower side of the supporting plate 11 to reinforce the plate and partially enclose the latch member D. A sheet metal housing 18 encloses the rear end of the channel thus formed and a rearwardly extending channel-like track 19 is secured thereto and serves to support the rear end portion of the extension carriage B. A cross-bar 20 is provided at the extreme end portion of the track 19 and is provided with rollers 21 and adjustable guide-members 22 for keeping the stationery 23 in alignment with the device. 30

The extension carriage B comprises a rectangular sheet metal frame 24 and is equipped at its front end with grooved rollers 25 which travel on the outer edge portions of the plate 11. The rear end of the frame has a guide yoke member 26 which straddles the track 19 and is equipped with a roller 27 to travel in the track. As best shown in Figure 3, the front end of the extension carriage is provided with a stud 28 which limits the travel of the frame in the slot 12. The frame is further provided with a downwardly extending stud 29a which cooperates with the latching bar D, as will be explained below.

The carbon holder C is of known construction and comprises a transverse plate 29 having a pair of downwardly extending studs 30 which is adapted to project through any transverse pair of apertures 31 provided in the frame 24. The weight of the device is usually sufficient to hold the carbon holder in its adjusted position, but, if desired, one of the studs may be threaded and provided on its lower end with a winged nut. The rear end of the plate is rounded, as indi-

cated at 32, to form a guide member for the stationery. The carbon holder has a pair of upwardly extending studs 33 for loosely impaling carbon holding latches 34 in the manner shown in Jensen Patent No. 2,000,641. Upward movement of the blades is limited by a pivoted bail 35, in the well known manner. A pair of guide fingers 36 is adjustably mounted in slots 37 to keep the stationery in lateral alignment.

10 The latching bar D is best shown in Figure 3 and comprises a pair of bars 38 which is pivotally mounted in the housing 18, as indicated at 39. The front ends of the bars 38 are joined, as indicated at 40, and the rear end is joined, as indicated at 41. A cam like strip 42 is fastened between the rear ends of the bars 38 and forms an inclined surface which bears against the stud 29 when the extensible carriage is moved to its rearmost position. As the pivot 39 is back 15 of the center of the bars, there is a tendency for the rear end portion 41 to be urged upwardly and thereby latch the extension carriage in its rearmost position. However, when the platen carriage of the typewriter 5 is down in the position 20 shown in Figure 5, a slotted portion 43 rests on the cross-bar 6 and holds the latch member in released position. Thus, it will be understood that when the platen carriage is raised and the extension frame permitted to roll rearwardly, it 25 will automatically become locked in its rearmost position. However, when the platen carriage is lowered, the bar 6 will engage the latch bar and release the extension carriage for forward movement.

30 35 The track 8 is positioned so that when the platen carriage is in its normal writing position, as illustrated in Figure 1, the plate 11 will be inclined downwardly and forwardly. However, when the platen carriage is raised to the position indicated in Figure 3, and by the dotted lines in Figure 1, the device will be inclined downwardly and rearwardly. It may be noted in this connection that the device is tilted about the track 8. When the platen is raised, the slots 40 45 in the saddle members 13, which are engaged by the cross-bar 6, permit the front end of the device to be raised by the cross-bar 7. The tilting action is useful in either the upper or lower position. When the front end of the device is 50 tilted upwardly, it is desired to move the stationery rearwardly and gravity assists in this movement. On the other hand, when the device is lowered to writing position, the latch is released, and gravity helps to permit forward movement 55 of the stationery and interleaved carbon.

The device is adapted to use ordinary continuous-form stationery or fanfold stationery. The stationery is led up over the rear of the device and the carbon is interleaved and attached to the bars 34 of the carbon holder. The front ends of the stationery are threaded between the platen and presser rolls, and, as the platen advances the stationery, the carbons and stationery roll forwardly. After a form has been filled in, 60 the platen is raised to release the stationery and permit the carbon holder to move back into latched position. The completed set of forms may then be drawn forwardly, stripping the car-

bon into the next succeeding set of forms, and be detached. The platen is then lowered and the next set of forms fed into writing position. This movement releases the carbon holder for forward movement.

The foregoing detailed description has been given for clearness of understanding only, and no unnecessary limitations should be understood therefrom, for some modifications will be obvious to those skilled in the art.

I claim:

1. A manifolding attachment for a typewriter having a rearwardly disposed transverse track and a laterally shiftable carriage in which is journaled an upwardly movable platen, comprising: a supporting frame attached to parts of the carriage so as to shift laterally therewith and the front end to move upwardly and downwardly with the platen; a fulcrum on said frame with antifriction means for supporting the rear portion of the frame on said track and disposed so that when the platen is raised the rear end of said frame will be lowered; a carbon holder slidably mounted for limited forward and rearward movement on the supporting frame; and locking means automatically effective to lock said carbon holder in a position back of said fulcrum when the platen is raised.

2. A device as specified in claim 1, in which the carbon holder has a projection and the locking means comprises a trigger member pivotally supported on the supporting frame and has on its rear end a latch to engage said projection, said trigger member having an inclined face adapted, when the platen is raised, to bear against and be depressed by the projection on the carbon holder while said carbon holder is being slid rearwardly to said extended position.

3. A device as specified in claim 1, in which the front end of said supporting frame is equipped with bifurcated attaching members disposed so as to engage cross rods on the platen carriage and maintain connection therewith by gravity.

4. A device as specified in claim 1, in which the locking means comprises a latch lever pivotally connected to the supporting frame in rear of the lever center of gravity so as to be urged by gravity into locking engagement with the carbon holder when the platen is in elevated position, and the front end of said lever being disposed so as to engage part of the carriage and release the carbon holder when the platen is lowered.

5. A manifolding attachment for a typewriter having a platen carriage in which is journaled an upwardly movable platen, comprising: a supporting frame having a fulcrum in rear of the typewriter and having its front end secured to parts of said carriage so as to rock to a forwardly inclined position when the platen is lowered and to a rearwardly inclined position when the platen is raised; an extension frame slidably mounted on said supporting frame and having carbon attaching means disposed in rear of said fulcrum; and means for locking said extension frame in its extended position disposed so as to be automatically released when the platen is lowered.

ALLEN B. COOKE.
